US0D1028392S

(12) **United States Design Patent** (10) **Patent No.:** **US D1,028,392 S**
(45) **Date of Patent:** **** May 21, 2024**

(54) **ELECTRIC WASHING AND DRYING MACHINE FOR LAUNDRY PURPOSE**

(71) Applicant: **LG ELECTRONICS INC.**, Seoul (KR)

(72) Inventors: **Junghwan Lee**, Seoul (KR); **Hoil Jeon**, Seoul (KR); **Sojin Park**, Seoul (KR); **Eunyoung Chee**, Seoul (KR)

(73) Assignee: **LG ELECTRONICS INC.**, Seoul (KR)

(**) Term: **15 Years**

(21) Appl. No.: **29/816,251**

(22) Filed: **Nov. 19, 2021**

(30) **Foreign Application Priority Data**

May 21, 2021 (KR) 30-2021-0024212

(51) **LOC (14) Cl.** **15-05**

(57) **CLAIM**

The ornamental design for an electric washing and drying machine for laundry purpose, as shown and described.

DESCRIPTION

FIG. 1 is a front perspective view of the electric washing and drying machine for laundry purpose showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference view showing the state of use that the display part at the front center panel of the claimed design has been operated.

The broken lines depict portions of the electric washing and drying machine for laundry purpose that form no part of the claimed design.

1 Claim, 8 Drawing Sheets
